UNITED STATES PATENT OFFICE.

JAMES M. WEAVER, OF LOS ANGELES, CALIFORNIA.

MORTISE-CATCH.

1,106,760.

Specification of Letters Patent. Patented Aug. 11, 1914.

Application filed November 22, 1913. Serial No. 802,394.

To all whom it may concern:

Be it known that I, JAMES M. WEAVER, a citizen of the United States, residing at Los Angeles, in the county of Los Angeles, State of California, have invented new and useful Improvements in Mortise-Catches, of which the following is a specification.

This invention relates to a mortise lock for small doors, drawers and the like, and the prime object of the invention is the provision of a simple form of mortise catch which will take the place of the force catches now commonly used and which will give all the advantages of a mortise spring bolt or spring catch lock.

It is one of the prime objects of this invention to provide a lock which may be very easily and quickly mounted upon a door or the like.

One of the reasons why force catches have been commonly used is that they are very easily and quickly set in a door, requiring only the boring of a cylindrical hole and setting the catch and the catch plate in place. I provide my mortise catch in cylindrical form so that it may be set in a door or the like by a simple boring of one or more cylindrical holes. I greatly reduce the amount of labor necessary for setting a mortise catch; and at the same time I provide all of the advantages which a mortise catch lock has over a force catch.

Although there may be many forms which my lock may take, I prefer the simple and inexpensive form described in the following specification and shown in the accompanying drawing, in which:

Figure 1 is a horizontal section showing my improved lock in place in a door or the like, Fig. 2 is a section of the lock itself taken as indicated by line 2-2 of Fig. 1, and showing the lock in its normal position, Fig. 3 is a section similar to that of Fig. 2 showing the lock in its position with the bolt retracted, Fig. 4 is a perspective detail of the bolt, Fig. 5 is a perspective detail of the bolt thrower, Fig. 6 is a perspective detail showing the body of the lock in section on line 6-6 of Fig. 2 and showing the mounting of the spring abutment plate therein.

In the drawings the numeral 10 may designate a door or the like and the numeral 11 may designate the stationary door casing. A catch plate 12 of any desired design may be mounted upon the casing; and my lock

is mounted in the door 10 so that its bolt 13 may engage the catch plate.

My lock includes a hollow cylindrical body 15 of suitable size and length (the drawing showing the lock greatly enlarged) a fair and usual diameter for the body being about one-half inch) a cylindrical bolt 13 movable longitudinally in the body; a spring 16 holding the bolt 13 normally forwardly as shown in Figs. 1 and 2; and a rotatable thrower 18 adapted to operate the bolt. The bolt 13 has the ordinary pivotal face 20 on its outer end so that it may act as a latch bolt. The main part of the bolt is cylindrical, as shown in the drawings, and immediately behind the main cylindrical portion of the bolt there are two opposite longitudinal extensions 21 which lie one above the other in the body 15 against the opposite walls thereof. These extensions are connected at their ends by transverse bar or pin 22, upon which pin the thrower 18 operates. A plate 23 extends across the body 15 in the space between the two extensions 21, this plate forming the abutment against which the spring 16 presses at one end, the other end of the spring being recessed into the cylindrical part of the bolt, as at 25. The abutment plate 23 is held in the body 16 by having its ends 26 and 27 extend through openings in the walls of the body 15. This is best shown in Fig. 6. The end 27 of the plate 23 is bifurcated and the furcations extending through two openings 27a in the body wall. The other end 26 of the plate 23 is reduced and extends through the opening 26a of the body wall. Immediately adjacent this opening 26a the body wall has a tongue 26b which may be pressed outwardly when the end 26 is inserted in the opening 26a and then be pressed inwardly again to its normal position so as to hold that end of the plate 23 in place. Simple assembly is thus provided for, the bolt 13, spring 16 and plate 23 being assembled in the relative positions shown and then thrust into the body 15 together, the plate 23 being turned diagonally so that the end 27 will reach the opening 27a before the end 26 reaches the opening 26a. Forcing the plate 23 farther inwardly forces the end 26 under the tongue 26b and forces the tongue 26b out until the end 26 passes the end of the tongue and the tongue springs in behind the end 26 of the plate 23.

The rotatable thrower 18 is of the form

best shown in Fig. 5. It has a cylindrical body portion 30 with a transverse cut or slot 31, leaving a web 32 which engages the pin 22. Normally the parts are in the positions shown in Fig. 2; rotation of the thrower moves the pin 22 and thereby moves the bolt 13. Excessive rotation of the thrower is prevented by a small stop pin or lug 35 on the thrower which engages with either of shoulders 36 on the bolt extensions 21. The thrower has a squared shank 40 engageable by a suitable knob 41. The knob is mounted upon a suitable plate 42 which may be secured to the outer surfaces of the door 10. In order to remove the thrower it is only necessary to push the bolt back into the body until the pin 22 clears the thrower. The thrower may then be removed from the body leaving the body with the bolt contained therein ready to be inserted in a door in the required position. It is only necessary to bore two cylindrical holes to insert my catch lock, one to contain the body and the other as shown at 45 in Fig. 1 to insert the thrower. The body is put into the position shown in Fig. 1 and the thrower is then inserted through the bore hole 45. The knob and plate are then placed upon the outer surface of the door. Placement of the catch plate 12 completes the mounting of the lock.

I claim—

1. A mortise catch, comprising a cylindrical tubular body, a cylindrical bolt therein, extensions of said bolt lying at opposite sides of the tubular body and a transverse pin extending between the extensions across the body, a spring pressing the bolt outwardly from the body, a rotatable thrower mounted in the body on an axis at right angles to the body axis and engaging said pin, the thrower being releasable from the pin and being removable from the body by movement along the thrower axis, and a knob for the thrower.

2. A mortise catch, comprising a cylindrical tubular body, a cylindrical bolt therein, extensions of said bolt lying at opposite sides of the tubular body and a transverse pin extending between the extensions across the body, a spring pressing the bolt outwardly from the body, a rotatable thrower mounted in the body on an axis at right angles to the body axis and engaging said pin, said thrower having a transverse slot and a web at the edge of the slot to engage the pin, the thrower being releasable from the pin and being removable from the body by movement along the thrower axis, and a knob for the thrower.

3. In a mortise catch, in combination, a cylindrical tubular body, a cylindrical bolt therein having a pair of extensions at its inner end at opposite sides of the body, a transverse pin connecting the two exten-

sions, and a thrower mounted in the body on an axis transverse to the body axis and transverse to the pin, said thrower having a slot cut across its axis with a web at one side adapted to act against the pin.

4. A mortise catch, comprising a cylindrical tubular body, a cylindrical bolt therein having two inner longitudinal extensions lying at opposite sides of the tubular body, a transverse pin extending between the longitudinal extensions across the body, an abutment plate extending across the body between the bolt and its said pin, a spring between the bolt and said plate and recessed within the bolt, and a thrower engaging the pin to move the bolt by its rotation.

5. A mortise catch, comprising a cylindrical tubular body, a cylindrical bolt therein having two inner longitudinal extensions lying at opposite sides of the tubular body, a transverse pin connecting the ends of the extensions across the body, an abutment plate extending across the body and fitted terminally into openings through the walls thereof, said abutment plate extending between said longitudinal extensions of the bolt and between the bolt and its said transverse pin, a spring recessed within the bolt and extending between the bolt and said abutment plate, a rotatable thrower mounted in the body on an axis at right angles to the body axis and engaging said pin, said thrower having a transverse slot therein and a web at the edge of the slot to engage the pin to move the bolt by its rotation, and a lug on the thrower adapted to engage with shoulders on said longitudinal extensions to prevent excessive movement of the bolt.

6. A mortise catch, comprising a cylindrical tubular body, a cylindrical bolt therein having two inner longitudinal extensions lying at opposite sides of the tubular body, a transverse pin connecting the ends of the extensions across the body, an abutment plate extending across the said body and adapted to be sprung into and to be secured in openings through the walls of said body, said abutment plate extending between the longitudinal extensions of the bolt and between the bolt and its said transverse pin, a spring recessed within the bolt and extending between the bolt and said abutment plate, a rotatable thrower mounted in the body on an axis at right angles to the body axis, said thrower having a transverse slot therein and a web at the edge of said slot to engage the pin and move the bolt along the body axis by its rotation and a lug on the thrower adapted to engage with shoulders on said longitudinal extensions to prevent excessive movement of the bolt, the thrower being releasable from the pin and being removable from the body by movement along the thrower axis.

7. In a mortise catch, the combination of a

cylindrical tubular body with a transverse plate having on one end an extension adapted to fit within an opening in the wall of said tubular body, the opposite end of said plate having an extension adapted to fit within an opening in the opposite wall of said body, said last mentioned opening having a spring tongue adjacent thereto adapted to be sprung aside to allow the said plate 10 to be put in place.

8. In a mortise catch, the combination of a cylindrical tubular body with a transverse plate having on one end an extension adapted to fit within an opening in the wall of said tubular body, the opposite end of said plate having an extension adapted to fit 15

within an opening in the opposite wall of said body, said last mentioned opening having a spring tongue adjacent thereto adapted to be sprung aside to allow the said plate 20 to be put in place, said plate having shoulders on each end adapted to bear against the inner face of said tubular body, all substantially as described.

In witness that I claim the foregoing I 25 have hereunto subscribed my name this 15th day of November 1913.

JAMES M. WEAVER.
